UNITED STATES PATENT OFFICE.

GEORGE W. COFFMAN, OF GARDEN CITY, KANSAS.

TYPE-WRITING MACHINE.

SPECIFICATION forming part of Letters Patent No. 702,706, dated June 17, 1902.

Application filed November 5, 1900. Renewed November 21, 1901. Serial No. 83,187. (No model.)

To all whom it may concern:

Be it known that I, GEORGE W. COFFMAN, a citizen of the United States, residing at Garden City, Finney county, Kansas, have invented a new and useful Type-Writing Machine, of which the following is a specification.

My invention relates to type-writing machines of that class designed to be carried in one's pocket and operated on any smooth flat surface that takes ink impressions; and my object is to produce a machine of this character which is thoroughly efficient and reliable in action and possesses the desirable features of simplicity, strength, durability, and cheapness of manufacture.

With these general objects in view the invention consists in certain novel and peculiar features of construction and combinations of parts, as hereinafter described and claimed, and in order that it may be fully understood reference is to be had to the accompanying drawings, in which—

Figure 1 is a perspective view of a type-writing machine embodying my invention. Fig. 2 is a vertical longitudinal section of the same. Fig. 3 is a front end view of the machine as engaged in making lower-case characters. Fig. 4 is a central transverse section 30 of the machine as engaged in making upper-case characters. Fig. 5 is a longitudinal section showing a type-bar-carrying-frame elevating means of slightly-modified construction, and Fig. 6 is a top view of the same. Fig. 7 shows a modified construction of machine. Fig. 8 is a bottom plan view of part of the flexible type-bar.

Referring to the drawings in detail, 1 designates the base of the machine, the same being in the form of a long narrow plate underlaid with a rubber strip 2 in order to obtain better cohesive relation with the surface to be written upon and eliminate chances of the base slipping, and thereby rendering the work inaccurate and inartistic and perhaps spoiling it, and this base is provided at its rear edge with a rack-bar 3, either circular in cross-section, as shown, or otherwise formed, and on its upper side said base is provided with a scale, as shown, to be used as a gage for start-

ing and ending the lines the same distance from the edge of the paper or other writing-surface.

4 designates a bed-plate about the same length but of greater width than the base-plate 55 by preference and formed at its front margin with a sleeve 5, embracing the rack-bar 3, and provided centrally with a notch or opening 6 to expose a portion of said rack-bar for a purpose which hereinafter appears. Said bed-plate is also provided centrally with an opening 7, and in order to insure legible printing the bed-plate is made as thin as possible near said opening, preferably by tapering it toward the same from all sides (see Fig. 4) to 65 enable the characters on the type-bar (hereinafter described) to be easily projected through the opening and have a square bearing on the paper or other surface printed upon. Near its outer end the bed-plate is 70 formed with an upwardly-projecting pin or arm 8 and near its opposite end with a pin 9, upon which is pivotally mounted to swing laterally a frame 10, U-shaped in cross-section, said frame being equal in length to the 75 bed-plate and in practice somewhat less than a half-inch in width and less than that in depth, though of course the exact proportions are not of importance in this connection. The bottom of this frame is provided, by preference, with a large opening 11 at its center and near its outer end with a transverse slot 12, embracing the projecting pin or arm 8, the engagement of the ends of the slot with said pin or arm limiting the lateral movement of said frame upon said bed-plate, and in order to hold the frame normally in its forward position against sleeve 5 of the bed-plate it is provided with a spring 13, having 80 its free or movable end bearing against the front side of said pin or arm 8, (see Figs. 1 and 3,) the power of the spring being sufficient to pull the frame forwardly to the position mentioned, as will be readily understood. When thus arranged, it will be understood by reference to Figs. 3 and 4 that the center of the frame is about vertically over the front edge of opening 7 and that when the frame is swung to the rear, as shown by Fig. 4, the center of the frame will be over 85 90 95 100

the rear edge of said opening. The object of this arrangement will be hereinafter explained.

As the most practical and durable inking device for the machine I secure upon the bottom of the frame at opposite ends of opening 11 the inking-pads 14. These pads need inking at infrequent intervals and then may be restored to their original condition and freshness by a little ink properly and easily distributed thereon.

15 designates a type-bar-carrying frame U shape in cross-section, the same being of equal length but narrower gage than frame 10 and 15 also inverted with respect thereto. Adjacent to pivot 9 said frame is pivoted, as shown at 16, to and within frame 10, so as to operate vertically, and is provided at a suitable point with a horizontal rock-shaft 17, carrying a 20 dog 18 at its front end, said dog extending downwardly and forwardly at the front side of frame 10 and having its tooth 19 intersecting the opening 6 of sleeve 5 and engaging one of the teeth of rack-bar 3, the tooth being of sufficient length to engage said rack-bar without regard to whether frame 10 occupies its front position against sleeve 5 (see Fig. 3) or its rear position, as shown in Fig. 4, and in order to hold this dog in the proper 25 position relative to the rack-bar a spring 20 spirally encircles the shaft and is secured at its opposite ends thereto and to a wall of the type-bar-carrying frame, as shown clearly in Fig. 4, the tendency of this spring obviously 30 being to hold the dog pressed downward upon the rack-bar and incidentally to utilize the dog as a lever for elevating the type-bar-carrying frame to its normal position, as shown in Figs. 1 and 2. The primary means for 35 causing said type-bar-carrying frame to assume and maintain normally its elevated position is a spring 21, secured to frame 10 in any suitable manner and exerting a pressure upward against one of the walls of frame 15, 40 preferably the rear wall. (See Figs. 2 and 4.) The weight of the type-bar-carrying frame is ordinarily sufficient to maintain it in about the relative position shown in Figs. 1 and 2; but to positively limit its upward movement 45 50 under the pressure of said springs I may secure one end of spring 21 to frame 15 and have a pin-and-slot connection, as at 22, between its opposite end and frame 10, as shown in Fig. 5. This obviously will guard against 55 frame 15 being raised high enough to permit spring 20 to throw the dog back of the notched portion 6 of the sleeve 5. Furthermore, by positively determining the altitude which frame 15 may assume regularity of pressure 60 is approximately attained in the manipulation of the machine, and better and faster work is the necessary result.

Frame 15 is provided with a pressure-roller 23 vertically over opening 7 and having the 65 lowest point of its periphery about in the plane of the lower edge of the frame and holding depressed below the same a portion of

the flexible type-bar 24. This type-bar is provided with upper and lower case letters and in addition with figures from "0" to "9," inclusive, and any other characters that may be desired and has its opposite ends secured to a slide-plate 25, or rather to blocks 26, depending from said slide-plate, for convenience in attaching the type-bar. This slide-plate is 70 supported against the upper portion of the frame 15 by means of a bridge-plate 27, and in order that the slide-plate may be adjusted said frame is provided with a longitudinal slot 28, through which the key-lever 29 may 75 operate, this key-lever being pivoted to plate 25 and constructed of spring metal in order that the free end may be raised sufficiently high to easily disengage the key 30, pivoted on its free end by preference from any of the 80 character-openings 31 with which it may happen to be engaged, said character-openings being formed in the reinforce-plate 32, secured to the upper side of frame 15, which 85 openings are arranged by preference in two 90 series, one near the front and one near the back margin of frame 15. In number the 95 openings exceed twenty-six by as many as there are figures and extra characters employed. The characters are preferably printed on a strip of paper or thin celluloid and secured between the upper side of frame 15 proper and the reinforce-plate containing the character-openings, as at 33. While the key-lever is pivoted as stated, it is obvious that 100 it may be secured rigidly to the slide-plate and its resiliency relied upon to permit the proper disengagement with the openings 31 near the front or rear edge of the frame. The key 30 is preferably flat, as shown, and swiveled 105 in order that in shipment it may be turned at right angles to the position it occupies and rest upon the reinforce-plate.

In practice, assuming that it is desired to use the machine and that the parts are arranged as shown, the base-plate is arranged upon a sheet of paper, a book, or other surface capable of taking ink impressions and held firmly with the left hand in any convenient manner. The key is then grasped between the forefinger and thumb of the right hand and, if necessary, swung laterally and longitudinally adjusted to dispose it over the proper character-opening 31. By this adjustment of the key the slide-plate 25 is moved 110 so as to dispose the character on the type-bar vertically over opening 7, which corresponds to the character below the key. If the first letter should be a capital, the operator, preferably with the forefinger of his left hand, 115 pushes frame 10 rearwardly to the position shown in Fig. 4, so as to dispose the front series of type characters, which are the upper-case letters or capitals, vertically over opening 7. The key is then pressed downward into the 120 registering character-opening with sufficient pressure to cause frame 15 to assume almost a horizontal position, the effect being that roller 23 forces the registering type char- 125

acter through opening 7 and upon the paper or other surface below. As this is accomplished such pressure is removed, and spring 21, assisted to some extent by spring 20, reëlevates frame 15 to its original position, and at the same time the pressure of the forefinger is removed from frame 10 and is instantly followed by such frame swinging forward under the power of spring 13 in a manner hereinbefore explained, and in this connection it will also be noted that with each depression of frame 15 most of the characters on the flexible type-bar are inked, so that they are all kept in condition to print at any time. The downward movement of the frame under the pressure of the key through the medium of the dog and rack-bar slides the bed-plate and the parts mounted thereon—i. e., the entire machine except the base-plate—one step, this movement terminating as the type engages the paper or other surface, so that the impression shall be made upon a relatively stationary surface, and consequently be clear and legible. The next letter being a lower-case letter, we will say, is printed in precisely the same manner as above described, except that frame 10 is not swung rearwardly upon the bed-plate, the result being that the desired character of the rear series on the type-bar, which represents the lower-case letters, is pressed downward through the registering opening 7, as will be readily understood.

In practice the machine can be manipulated with a very fair degree of rapidity, and a line of any length can be printed by noting the point on the scale opposite the point where the last impression was made and marking or otherwise locating such point upon the paper or on a straight-edged guide held against the front edge of the base-plate and then sliding the entire machine, including the base-plate, along the edge of said guide the desired distance, the guide being employed simply to insure a straight line of printing. The dog is now held out of engagement and the bed-plate and superposed parts adjusted until the dog, which is preferably in transverse alinement with opening 7, registers with the point of identification referred to. The operation of the machine may then be proceeded with in the usual manner. When a new line is to be printed, to insure parallelism and uniformity in the distance between the lines the machine is moved bodily downward until the rear edge of the bed-plate registers with the upper or lower margin of the printed line, as desired. In the former case the lines will be closer together than in the latter.

In Fig. 7 I show a spring 13^a secured to the hinge end of the bed-plate and pressing forwardly at its free end against frame 10 in order to hold the latter and frame 15 in position to print the lower-case letters. In said figure I also show a modified means for limiting the upward movement of frame 15 un-

der the pressure of spring 21, this construction comprising a set-screw 10^a, carried by frame 10 and projecting into a short slot 15^a in frame 15, which set-screw can be withdrawn from said slot easily and quickly to permit frame to be swung upward to a vertical position to give convenient access for reinking the pads 14, as will be readily understood.

From the above description it will be apparent that I have produced a type-writing machine which embodies the features of advantage enumerated as desirable in the statement of invention, and while I have illustrated and described the preferred embodiment of the same it is clearly susceptible of various modifications as regards its form, proportion, detail construction, and arrangement of the parts without departing from the essential spirit and scope or sacrificing any of the advantages of the invention.

Having thus described the invention, what I claim as new, and desire to secure by Letters Patent, is—

1. In a type-writing machine, a base, a rack-bar thereon, a bed-plate longitudinally adjustable relatively to the base and provided with an opening, a frame mounted on the bed-plate and provided with an opening register-95 ing with that of the bed-plate, a second frame pivoted to work vertically in the first-named frame at one end, and yieldingly upheld, and provided with character-indicating points, a longitudinally-adjustable slide-plate mount-100 ed in said vertically-operating frame, a flexible type-bar secured to said plate, means for holding depressed that portion of the flexible type-bar which is vertically over the bed-plate opening, a key-lever also secured to said plate, 105 a key on said lever, and adapted when registering with one of said character-indicating points to dispose the corresponding character on the type-bar vertically over the bed-plate opening, and a dog pivotally depending 110 from the said second frame and engaging said rack-bar, substantially as described.

2. In a type-writing machine, a base, a rack-bar thereon, a bed-plate longitudinally adjustable relatively to the base and provided 115 with an opening, a frame mounted on the bed-plate and provided with an opening register-120 ing with that of the bed-plate and with an ink-pad at opposite ends of said opening, a second frame pivoted to work vertically in the first-named frame at one end and yieldingly upheld, and provided with character-indicating points, a longitudinally-adjustable slide-plate mounted in said vertically-operating frame, a flexible type-bar secured to 125 said plate, means for holding depressed that portion of the flexible type-bar which is vertically over the bed-plate opening, a key-lever also secured to said plate, a key on said lever, and adapted when registering with one of 130 said character-indicating points to dispose the corresponding character on the type-bar vertically over the bed-plate opening, and a dog pivotally depending from the said sec-

ond frame and engaging said rack-bar, substantially as described.

3. In a type-writing machine, a base, a frame movable longitudinally and laterally thereof and provided with an opening, a vertically-movable frame mounted on the first-named frame and provided with character-indicating points, means for holding said vertically-movable frame pressed yieldingly upward, a flexible type-bar adjustably mounted in the vertically-movable frame, and having one or more rows of type, and means, by reference to said indicating-points, to dispose any desired character on the type-bar vertically over the opening of said longitudinally-movable frame, substantially as described.

4. In a type-writing machine, a base, a frame movable longitudinally and laterally thereof and provided with an opening, means for yieldingly holding said frame in its forward position, a vertically-movable frame mounted on the first-named frame and provided with character-indicating points, means for holding said vertically-movable frame pressed yieldingly upward, a flexible type-bar adjustably mounted in the vertically-movable frame, and having one or more rows of type, and means, by reference to said indicating-points, to dispose any desired character on the type-bar vertically over the opening of said longitudinally-movable frame, substantially as described.

5. In a type-writing machine, a base, a frame movable longitudinally and laterally thereof and provided with an opening, a spring holding said frame normally in its forward position, a vertically-movable frame mounted on the first-named frame and provided with character-indicating points, means for holding said vertically-movable frame pressed yieldingly upward, a flexible type-bar adjustably mounted in the vertically-movable frame and having one or more rows of type, and means, by reference to said indicating-points, to dispose any desired character on the type-bar vertically over the opening of said longitudinally-movable frame, substantially as described.

6. In a type-writing machine, a base, a rack-bar thereon, a bed-plate longitudinally adjustable relatively to the base and provided with an opening, a frame mounted on and pivoted to the bed-plate near one end, to work laterally, and provided with an opening registering with that of the bed-plate, a second frame pivoted to work vertically in the first-named frame adjacent to the pivotal point of connection of the latter with the bed-plate,

and provided with character-indicating points, a longitudinally-adjustable slide-plate mounted in said vertically-operating frame, a flexible type-bar secured to said plate, means for holding depressed that portion of the flexible type-bar which is vertically over the bed-plate opening, a key-lever also secured to said plate, a key on said lever, and adapted when registering with one of said character-indicating points to depress the corresponding character on the type-bar vertically over the bed-plate opening, and a dog pivotally depending from the said second frame and engaging said rack-bar, substantially as described.

7. In a type-writing machine, a base, a rack-bar thereon, a bed-plate longitudinally adjustable relatively to the base, and provided with an opening, a frame pivoted near one end to the base and having a pin-and-slot connection with it at the opposite end, and provided with a registering opening and ink-pads at opposite ends of said opening, a second frame pivoted to work vertically in the first-named frame and provided with character-indicating points, a roller, and a dog, the latter engaging said rack-bar, a spring holding said frame normally elevated, a slide-plate mounted in said frame, a flexible type-bar connected at its opposite ends to said slide-plate and underlying said roller, a lever connected to said slide-plate and provided with a key at its free end to register with one or another of said character-indicating points, substantially as described.

8. In a type-writing machine, a base, a bed-plate having an opening, a frame upon the bed-plate and provided with a registering opening and with ink-pads, a second frame adapted to fold down into the first-named frame and provided with a longitudinal slot and character-indicating openings, a slide-plate fitting in said second frame, a flexible type-bar carried by the slide-plate, a roller depressing that portion of the type-bar which is vertically over the registering openings, a lever extending through said slot and secured to said slide-plate, and a key to engage one of the character-openings, and thereby dispose the corresponding type of the type-bar over said registering openings, substantially as described.

In testimony whereof I affix my signature in the presence of two witnesses.

GEORGE W. COFFMAN.
